COMPONENT OF A MULTI-PIECED TOY
OR THE LIKE

James Baldwin Swett, Barrington, and Harold Prescott Ashton, Providence, R.I., assignors to Dart Industries, Inc., a corporation of Delaware

Filed July 3, 1968, Ser. No. 12,603

Term of patent 14 years

Int. Cl. D21—02
U.S. Cl. D34—5

FIG. 1

FIG. 2

FIG. 3

FIG. 4

FIGURE 1 is a perspective view of a component of a multi-pieced toy embodying the ornamental design of the invention;

FIGURE 2 is a perspective view taken from a different angle as shown by the position of the holes and showing the component in a broken apart relationship;

FIGURE 3 is a top view of the component as shown in FIGURE 1; and,

FIGURE 4 is a bottom view of the component shown in FIGURE 1.

We claim:

The ornamental design for a component of a multi-pieced toy or the like, substantially as shown.
